HUGH CHRISTIE, OF MORRISANIA, NEW YORK, ASSIGNOR TO ISRAEL FOSTER, OF PHILADELPHIA, PENNSYLVANIA.

Design No. 4,176, dated June 28, 1870.

DESIGN FOR A CARPET-PATTERN.

The Schedule referred to in these Letters Patent and making part of the same.

I, HUGH CHRISTIE, of Morrisania, county of Westchester, State of New York, have invented or produced a Design for a Carpet-Pattern, of which the following is a specification.

The accompanying photographic illustration fully represents my design, which consists of the figures A and B, and surrounding ornamentation C, the whole being arranged as shown.

The figures A are bounded by the straight and angular lines *d* and *e*, and have a wide border, within which, at equal distances apart, is arranged a number of spots, *f*, and in the center of each figure is an ornament, *h*.

The angles of the figure A are occupied by ornaments, *i*, of the character clearly shown in the drawing.

The figures B are square or diamond-shaped, and

have at each corner a design, *k*, somewhat resembling the ornaments *i*; and from the sides of the said figure spring the scroll-like or foliated ornaments C, above referred to, which occupy the ground-work of the carpet, and between the ends of which are arranged the small four-armed figures *m*.

Irrespective of the colors employed,
I claim—

The design for a carpet-pattern, substantially as described, and as represented in and by the accompanying drawing.

In testimony whereof I have signed my name to this specification in the presence of two subscribing witnesses.
